EMILIUS WILLIAM SCHERR, JR., OF NEW YORK, N. Y., ASSIGNOR TO THE AEOLIAN COMPANY, A CORPORATION OF CONNECTICUT.

AUTOMATIC MUSICAL INSTRUMENT AND MUSIC-SHEET.

1,372,560.

Specification of Letters Patent.

Patented Mar. 22, 1921.

Application filed August 23, 1916. Serial No. 116,484.

To all whom it may concern:

Be it known that I, EMILIUS WILLIAM SCHERR, Jr., a citizen of the United States, residing at New York, in the county and State of New York, have invented certain new and useful Improvements in Automatic Musical Instruments and Music-Sheets, of which the following is a specification.

My present invention is an improvement 10 on automatic musical instruments having laterally-traveling music-sheets with vertical tracker-bars. I have discovered that in playing this type of instrument, one has a certain unpleasant, leaning-backward sensation which I have found is eliminated by more or less inclining the tracker-bar and the laterally-traveling music-sheet.

An additional object and advantage of the foregoing is that one margin of the music-sheet is thereby conveniently brought nearer the player than the other, upon which near margin the eyes will naturally focus and at the same time see the rest of the sheet to the far edge, with little or no change in the focus 25 or position of the eyes. With the vertically running sheet, on the other hand, when positioned as usually so that the eyes of the player are about on a level with its middle portion, the eyes are directed as much to one part or margin of the sheet as to the other, and become tired in shifting their focus up and down between the two edges of the sheet. This is especially so when the tempo and dynamic lines and the other indicia for 30 the playing of the sheet are located, as heretofore, all over the sheet, so that to read them the eyes must continuously travel from the top of the sheet to the middle or bottom and back again. This defect which I have 35 discovered in the old laterally-traveling music-sheet, I have remedied by placing all of the aforesaid indicia principally on one margin of the sheet, preferably on the margin nearest the eyes of the player, because, 40 as above indicated, the eyes will then be able to focus primarily on the indicia and yet, and with little or no change of focus, or additional effort, will sight in the general line of vision the rest of the sheet to the far margin, including the music perforations to which the near marginal indicia relate, as well as any additional indicia on the 45 middle or far margin of the sheet.

The invention will be readily understood 50 from the following description when con-

sidered in connection with the accompanying drawing, which latter shows only some of the specific embodiments my invention is adapted to take.

In said drawing:

Figure 1 is a vertical section through the upper part of an upright piano, showing a tracker bar and music roll, &c., in side elevation;

Fig. 2 is a plan view of the means for 65 operatively supporting the tracker bar and for driving the music roll and take-up spool;

Fig. 3 is a front elevation, looking from left to right at Fig. 1;

Fig. 4 is a side elevation, partly in section, 70 taken on line 4—4 of Fig. 3, looking in the direction of the arrows;

Fig. 5 is a plan view of the music roll with the music sheet partly unrolled;

Fig. 6 is a sectional view from side to side 75 through the tracker box; and

Fig. 7 shows in side elevation a modified means for inclinably supporting the tracker bar and music sheet.

I will now describe the specific devices 80 of the drawings showing my invention applied to an upright piano, although, of course, it is applicable also to a grand piano and to automatic musical instruments generally:

1 is the tracker box; 2 is an uprightly disposed tracker bar supported in said box (compare Figs. 1, 3 and 6). The tracker box is pivotally suspended from an axis 3, to swing through an opening in the case of 90 the instrument so as to assume an inclined playing position, such as that shown by the full lines in Fig. 1; or, when out of play, to be returned within the casing of the instrument into the dotted position 1^a. The music 95 sheet travels laterally, preferably from right to left. The take-up spool 4 is therefore supported at the left of the tracker between suitable end bearings, and the music roll 5 is insertible at the right between the usual 100 end bearings for the music-roll.

The plan view in Fig. 2 shows the pivotal suspension of the tracker box, comprising fixed standards 6, 6, supported within the piano casing, and brackets 7, 7, on the ends 105 of the tracker-box, the brackets and standards being pivoted together at 3. 9—9 are shafts suitably supported as shown by bearings on the top of the tracker box in alignment with the pivots 8. Each shaft has a 110

sprocket wheel 10 adapted to be suitably connected and driven in any well understood manner from the motor of the instrument. 11 is a spiral gear wheel on each shaft in connection with another spiral gear 12 on the upper bearings for the music roll and the take-up spool. The result is that when the left-hand shaft 9 is driven from the motor it drives the take-up spool to unwind 10 or play the music-sheet from right to left across the tracker-bar. Reversely, when the motor is connected to drive the right hand shaft 9, the latter in turn rewinds the music-sheet on to the music-roll spool.

15 Any suitable means may be employed to support the tracker box at any inclination preferred by the performer sitting at the front of the instrument.

My improved music-sheet is shown in the drawings, especially Fig. 5. It embodies on the lower margin the following: first, the words and musical score of a song, for instance, of which the music perforations 14^a play the air or melody and the perforations 14^b the accompaniment; second, the tempo line 15, by following which with the pointer 16, connected with the motor of the instrument, the speed of said motor and the travel of the music-sheet are controlled, as is well understood in the art; third, the dynamics expression line 17 which is the same as the usual dynamics line, except that it is located on this same margin of the sheet, and is compressed into a narrower width.

35 In addition, there are shown tempo-line marks 18, consisting of vertical leads from the points on the dynamics line where said line begins a new or changed indication, which fact will therefore be brought automatically to the player's notice as his tempo pointer nears the points 18 in following the tempo line.

Similarly, 19, 19, are tempo line marks or leads, referring to rhythm marks 20 on the dynamics line, thereby automatically calling the player's attention to said rhythm marks, so that he will play the vertically alined note-perforations with a slightly greater accent or a slightly greater degree 50 of dynamics than that indicated by the dynamics line for the other unaccented notes.

Similarly there may be tempo line marks or leads 21 in vertical alinement with the notes to be sung to show their occurrence.

55 Finally, rest or pause marks 22 are located on or near the tempo line to indicate the end of phrases, passages or periods in the musical composition, the marks indicating by their length or size the duration of the pause or expressive retard to be observed in the playing of the music-sheet.

Such a music-sheet is played to the best advantage when traveling laterally and inclining upwardly away from the player, so

that the eyes focusing primarily on the indicia on the lower margin of the sheet where it is traveling across the tracker, will be able to sight the rest of the sheet's width therefrom with minimum effort, especially the 70 note perforations in crosswise-of-the-sheet alinement, to which the indicia relate. Of course the degree of inclination depends also upon the individual player, and especially upon the height of the tracker box relative 75 to the player's eye level.

When the indicia are on the sheet's lower margin it will be seen by tilting Fig. 5 before the eyes, that the lower the position of the sheet below the eye level the smaller may 80 be its inclination, even to the extent of making it almost or quite horizontal, or inclining its far edge downwardly below the horizontal. On the other hand, the higher the sheet above the eye level the greater with 85 advantage can be its approach toward verticality. However, whatever the level, it will be found that inclining the sheet out of the true horizontal or vertical will prove advantageous and best for its reading with 90 minimum tiring of and confusion to the eyes.

The dotted lines 1^x, in Fig. 1, show a modification where the tracker box does not swing so as to be adjustable to different angles of inclination, but is fixed or rigidly built into the instrument so that its vertical tracker bar and laterally traveling music-sheet are permanently inclined.

Fig. 7 shows another modification where- 100 in the tracker box is supported on the links 26, 27, said links being pivotally supported at 26^a and 27^a from the frame of the instrument. There are a pair of these links 26, 27, at each end of the tracker box, the result being that said box and its tracker and laterally traveling music sheet can be supported through a still greater range of inclination to suit the eye level of the individual player. The full lines show one of the playing positions and the dotted lines out-of-playing position. The drive is delivered by chains 28 from sprockets 29 to sprockets 30, and thence through spiral gears like the gears 11 and 12 heretofore described in connection with Fig. 2, to the take-up spool and music-roll. Any suitable means is provided for maintaining the adjustment of the tracker box.

110 What I claim is:

1. In an automatic musical instrument adapted to play a music sheet having note perforations in the body thereof and indicia pertaining to such note perforations, the combination of means for operatively 125 supporting said music sheet to travel endwise in a direction from one side toward the other side of the instrument while said sheet lies in a sufficiently inclined position relatively to the front of the instrument to en- 130

able the performer to visually relate the note perforations in the body of the music sheet with the indicia pertaining thereto, and automatic playing means to coöperate with the music sheet to play it.

2. In an automatic musical instrument, the combination of a music sheet having note perforations and indicia arranged in alinement transversely with the note perforations to which they relate, means inclined forwardly and downwardly relatively to the front of the instrument for operatively supporting the music sheet to travel endwise in a horizontal direction with the music sheet lying in a substantially inclined position before the performer, and automatic playing means to coöperate with the music sheet to play it.

3. In an automatic musical instrument adapted to play a music sheet having note perforations in the body thereof and related indicia upon a margin of the sheet, means inclined substantially in a direction forwardly and downwardly relatively to the front of the instrument for operatively supporting the music sheet to travel endwise in a direction from one side toward the other side of the instrument while the music sheet lies in a correspondingly inclined position to enable the performer more easily to visually relate the note perforations to the corresponding indicia located on the forward lower margin of the music sheet.

4. In an automatic musical instrument, a tracker-bar substantially inclined downwardly and forwardly relatively to the front of the instrument, a music sheet having note perforations in the body thereof, and related indicia upon the lower margin of the music sheet which is nearest to the performer, and means for operatively supporting said music sheet to travel longitudinally and horizontally across said inclined tracker-bar while

the music sheet is substantially inclined in a direction transversely of its length with the indicia thereon located at the forward lower margin of the music sheet.

5. In an automatic musical instrument, a tracker-bar substantially inclined downwardly and forwardly relatively to the front of the instrument so that its lower end will be nearest to the performer, a music sheet having note perforations in the body thereof and indicia upon one of its margins, said indicia being in transverse alinement with and relating to note perforations in the body of the sheet, and spools having their axes inclined to conform substantially with the inclination of the tracker-bar and operative to support the music sheet and to cause it to travel longitudinally across said inclined tracker-bar in a direction from one side toward the other side of the instrument while the music sheet is substantially inclined in a direction transversely thereof and with the margin of the music sheet having the indicia thereon located toward the lower edge of the sheet so that said indicia will be nearest to the performer.

6. In an automatic musical instrument for playing a laterally traveling music sheet, the combination of a tracker bar inclined longitudinally in a direction forwardly and downwardly relatively to the front of the instrument, means for operatively supporting a music sheet to travel endwise across said inclined tracker bar and in a direction from one side toward the other side of the instrument while said sheet lies in a correspondingly inclined position, and automatic playing means to coöperate with the music sheet to play it.

In testimony whereof, I have signed my name to this specification this 22d day of August, 1916.

EMILIUS WILLIAM SCHERR, J.R.
